FEEDING DEVICE

John Peters, Detroit, Mich.

Application April 22, 1940, Serial No. 330,873

3 Claims. (Cl. 29—62)

This invention relates generally to lathes and similar machines for turning and feeding stock to cutting tools and relates more particularly to feed devices therefor.

It is an object of the present invention to provide for a rod stock feeding machine, a new and improved friction feed device of a character such that the frictional force exerted will not diminish materially over long periods of time.

Another object of the invention is to provide a new and improved friction feed device which will require little or no attention or replacement of parts.

A further object of the invention is to provide a device of the above mentioned character which is efficient in operation and of durable construction and one which will not scratch the surface of the stock.

Other objects of the invention will become apparent from the following detailed description taken with the accompanying drawing which form a part of this specification and in which,

Figure 1 is a side elevational view of my improved feed device.

Figure 2 is a top plan view of the device shown in Figure 1.

Figure 3 is a view shown in longitudinal section of the feed device.

Figure 4 is a view in cross section of the feed device taken along the line and in the direction of the arrows 4—4 of Figure 1.

Figure 5 is an end view of the device looking from right to left of Figure 1.

Figure 6 is a fragmentary view of a modified form of the device of Figure 1, and

Figure 7 is a fragmentary view shown partly in elevation and partly in section of a machine for which my device is adapted for use.

Referring to the drawing by characters of reference, the machine shown in Figure 7 includes a frame, of which only an upper portion 10 is shown, the frame 10 adjacent its upper end having horizontally-spaced, aligning, hollow bosses 11 in which an open-ended tube 12 is rotatably mounted. Fixed to the tube 12, a gear 13 is provided which may be driven by any suitable source of power to rotate the tube 12. As shown, the tube 12 extends through the frame 10, and onto one end of the tube is screw-threaded a chuck member 14, which may be of any suitable well-known type, having a tapered end or wedge portion 15. Within the tube 12 there is provided a second tube 16 having a tapered end portion 17 which engages in the tapered chuck portion

15 for frictionally coupling the two tubes for rotation together.

Reciprocable in the inner tube 16 is my improved friction feed device designated in general by the numeral 18. The feed device 18 includes a carrier member 19 which is slidably received and guided in the tube 16 and the member 19 is provided with a reduced threaded portion 20 which screw threads into the inner 10 end of an open-ended tube 21a which is slidably received and guided in the tube 16. Carried by the member 19 there is provided a plurality of friction members 21, of which there are two in the present instance, these friction members 21 being elongated and extending longitudinally within the tube 16 toward the chuck 14. The rod stock, designated by the numeral 22 extends through the tubular carrier 19 between the friction members 21 and through an aperture in the cooperative chuck member 17 to a cutting tool or tools, not shown, but which tools may be any of the well-known type employed with lathes and similar machines for making various parts from rod stock. Fixed in and to the carrier member, an open-ended tube 22a is provided, to aid in guiding the rod stock when the stock is initially positioned in the machine.

On the opposite end of the tube 16 from the chuck 14, an out-turned flange 23 provides an abutment surface for the ends 24 of a pair of toggle arms 25 which are pivoted, as at 26, to a suitable fixed support 27. Slidably on and along the outer tube 12 there is a toggle actuator 28 having a rounded outer surface 29 which engages ends 30 of the toggle arms 25, the ends 30 preferably being rounded as shown to reduce friction between the parts.

On a horizontal shaft 32 supported by the frame 10, there is a shifter member 33 having a shifter fork which engages in an external annular groove 34 provided in the toggle actuator 28. The shifter member 33 is provided with an integral follower member 35 which engages in a cam groove 36 provided in the outer periphery 45 of a rotatable cam member 37 which is rotatably mounted on a horizontal shaft 38, the shaft 38 being parallel to the shaft 32 and being supported by the frame 10. As the cam 37 rotates, the shifter member 33 is shifted along its shaft 32 50 to move the toggle actuator 28 toward and/or away from the toggle arms 25. When the toggle arms are moved outwardly or away from each other, it will be seen that the tube 16 is moved to the right, wedging the tapered end portion 17 thereof in the chuck 14. The tapered end

portion 17 is provided with longitudinal slots 40 which permit the split end sections to be moved inwardly and grip the rod stock 22 so that the stock will be rotated with the chuck by the driving means driving the gear 13.

A second reciprocable shifter member 42, slidably mounted on the shaft 32, is provided with a shifter fork 43 which engages in an annular groove 44 provided by a pair of spaced out-turned flanges on the outer end of the tube 21a.

Like the shifter member 33, the shifter member 42 is provided with an integral follower member 45 which engages in and follows a cam groove 46 provided in the outer periphery of a rotatable cam member 47, which is mounted on the shaft 38. It will be seen that as the cam member 47 rotates, the member 42 will be shifted to reciprocate the tube 21 and consequently will reciprocate the feed device 18 which is secured to the tube 21.

Referring now in more detail to the feed device 18, the carrier member 19 thereof is provided with spaced pairs of lugs 48 to receive end portions respectively of the friction members 21 which are attached or connected to the lugs 48 by transverse pins 49. In order that the friction members 21 may move bodily inward to grip the rod stock 22, the pin receiving apertures, as at 50, in the lugs 48 are elongated transversely thereof to permit the pins 49 to move therein so that the entire inner surfaces of the friction members 21 will contact the surface of the rod stock 22. The outer surfaces of the friction members 21 are recessed as at 51 and secured to these recessed surfaces are oppositely disposed anchor plates 52. As clearly shown in Figure 1, the anchor plates 52 are provided with spaced tabs or hooks 53, to which are secured opposite ends of helical coil springs 54 which are carried solely by the friction members 21. Preferably a plurality of these springs 54 is provided on opposite sides of the friction members 21 and these springs urge the friction members inwardly against the surface of the rod stock 22. The inner surfaces of the friction members 21 are rounded as at 55 to conform to the rod stock and these friction members may be used for gripping stock of various sizes within limits. Preferably the friction members 21 terminate at their outer or free ends in substantially semi-circular end portions 56 which are slidably received and guided in the tube 16.

Referring now to the modification of Figure 6, in this construction instead of the helical coil springs 54, a pair of leaf springs 57 is provided to hold the friction members 21 against the rod stock 22. The leaf springs 57 are carried by the tubular carrier member 19 and may be secured thereto by screws 58 or by other suitable means. The leaf springs 57 extend longitudinally of the elongated friction members 21 and adjacent their free ends the leaf springs may be slightly bowed, as at 58, where they engage the friction members 21.

In operation, when the parts are in the positions shown in Figure 7, the rod stock 22 is being rotated by reason of the chuck 14 clamping the cooperating chuck member 17 tightly to the rod stock 22 and during this operation the rod 22 rotates relative to the friction feed device 18. As the cam 37 rotates, it moves the shifter member 33 to the right, which in turn moves the toggle actuator 28 to the right, permitting the toggle arms 24 to release the chuck tube 16, which is moved slightly to the left by the com-

pressed chuck jaw 17, thus releasing the rod stock 22. As the above operation takes place, the cam 47 operating through the shifter member 42 shifts the tube 21 and the friction feed 18 to the right. Since the chuck member has been released by the chuck member 14, the friction between the friction members 21 and the shaft 22 will now be sufficient to feed or advance the rod stock 22 to the right for the next operation thereon. After the rod 22 has been advanced by the feed device 18, the cam 37 operates through the shifter member 33 to move the actuator 28 to the left. As the actuator 28 moves to the left, it pivots the toggle arms 25 which operate to shift the tube 16 to the right to wedge the split tapered end 17 thereof in the chuck member 14 and again grip the rod 22 to rotate the same with respect to the tools operating thereon. Also, the cam 47 acting through its follower or shifter member 42, retracts the feed device 18 preparatory to again advancing or feeding the rod 22 when the chuck is released.

It will now be seen that I have provided a new and improved rod stock feed device having a plurality of rigid, replaceable friction members or shoes carried by a reciprocable carrier member in such a manner as to present a large friction surface for engaging the stock. Also, it will be appreciated that the frictional force exerted by the springs through the friction members will not quickly diminish, with the result that the device will need little or no attention over long periods of time. In addition, the friction members of the present feed device are carried by the carrier member in such a manner that the springs act to bodily move the friction members radially into engagement with the rod surface such that the frictional force acting through the friction members is directed radially with respect to the axis of the rod stock.

While I have shown and described my invention in detail, it is to be understood that the same is to be limited only by the appended claims for many changes may be made without departing from the spirit and scope of the invention.

What I claim is:

1. In a machine of the character described for feeding rod stock longitudinally, a carrier member having an aperture therethrough to receive the stock, a plurality of elongated friction members between which the stock extends longitudinally thereof, means for loosely and pivotally attaching said friction members to said carrier member comprising pivot elements engaging transversely elongated bearing bores whereby to provide for movement of said friction members inwardly to engage the rod stock, and spring means connected between said friction members and urging said friction members into engagement with the rod stock.

2. In a machine of the character described for feeding rod stock longitudinally, a carrier member having an aperture therethrough to receive the rod stock, a plurality of elongated friction members carried by said carrier member, means for attaching said friction members to said carrier member comprising pivot elements engaging transversely elongated bearing bores whereby to provide for inward movement of said friction members bodily and relatively to said carrier member to grip the rod stock, and multiple spiral springs connected between said friction members for urging said friction members against the rod stock.

3. In a machine of the character described for

feeding rod stock longitudinally, a carrier member having an aperture therethrough to receive the rod stock, a pair of oppositely disposed elongated friction members carried by said carrier member, means for connecting corresponding ends of said friction members to said carrier member comprising pivot elements engaging transversely elongated bearing bores whereby to provide for bodily movement of said friction

members inwardly to grip the rod stock, a spring holder secured to each of said pair of friction members and extending transversely thereto, and a plurality of springs connected between said spring holders on opposite sides of said friction members urging said friction members together against the rod stock.

JOHN PETERS.
